UNITED STATES PATENT OFFICE.

LACEY H. EVANS, OF LANSDOWNE BOROUGH, PENNSYLVANIA.

VERTICAL FILE.

1,137,389.

Specification of Letters Patent. Patented Apr. 27, 1915.

Application filed January 29, 1913. Serial No. 744,945.

To all whom it may concern:

Be it known that I, LACEY H. EVANS, a citizen of the United States, residing at No. 101 East Stewart avenue, in the borough 5 of Lansdowne, in the county of Delaware and State of Pennsylvania, have invented certain new and useful Improvements in Vertical Files, of which the following is a specification.

10 This invention relates to improvements in vertical files.

An object of my improvements is to provide a file in which phonograph disk records, or other articles may be conveniently and 15 compactly stored each in its own vertical compartment to preserve the record from abrasion.

Another object of my invention is the provision of means whereby the stored articles 20 may be selectively withdrawn from the file and replaced with facility.

A still further object of my invention is to provide a file for the storage of phonograph disk records or other articles that 25 can be put in a cabinet, case or other convenient receptacle which will protect the stored articles from dust, etc.

With these and other objects in view, the invention consists in the novel construction, 30 combinations and arrangement of parts, as will be hereinafter described with reference to the accompanying drawings.

In the said drawings Figure 1 is a front elevational view of the invention and Fig. 35 2 a vertical cross sectional view of the same taken on the line *a—a* of Fig. 1.

Similar numerals refer to similar parts in both views.

The vertical file may consist of the partitions 1—1 which are supported at the rear 40 by the two rods 2—2 passing through holes in the partitions which are separated by the rings 3—3. The ends of the rods 2—2 are fastened to the end supports 4—4 by means 45 of the screws 5—5 passing through said supports 4—4 and screwed into the rods 2—2 at such location as to suspend the partitions 1—1 above and clear of the strips 6—6. These strips 6—6 on which the stored 50 articles rest, are fastened at their ends to the end supports 4—4 by means of screws 7—7 passing through the end supports 4—4 and said strips are spaced so that the disks of predetermined size will bear only on their 55 inside edges. The supports 4—4 may be

omitted, in which case the ends of the rods 2—2 might be fastened directly to the sides of the cabinet case or other convenient receptacle in which the file is to be used and the strips 6—6 might be fastened directly 60 to the bottom of the inclosing receptacle.

Numerals or other characters are marked on the tabs 8—8 which may be parts of the partitions and formed by cutting away a portion of the upper part of each partition. 65 They are arranged in convenient series one tab below the other on successive partitions so that all may be easily seen. These tabs 8—8 may be attached to the partitions 1—1 instead of being a part of them and they 70 may project beyond the main part of the partitions or they may be omitted, in which case the index characters may be marked on the corner of the partitions.

It is to be noted that the partitions 1—1 75 swing on vertical axes passing through the centers of rods 2—2; that the stored articles rest between the partitions and on the inside edges of the strips 6—6 which prevent the disks from rolling; and that the stored articles may slide laterally on these strips 6—6. 80 It is further noted that the stored articles are normally hidden from view although any one may be obtained through reference to the index characters upon the tabs 8—8. 85 Placing the finger on the index character representing the desired stored article, the partition is pushed aside enough to get several fingers between the partitions when both the partitions and the other stored 90 articles can easily be moved enough to grasp the desired stored article. The article is returned in the same manner.

Having thus described my invention what I claim and desire to protect by Letters Patent of the United States is:—

A vertical file consisting of end supports; horizontal parallel strips extending between the lower portions of said supports; horizontal parallel rods extending in a vertical plane between the end supports at the back of the file; with vertical partitions mounted on said rods and free to swing on vertical axes.

In testimony whereof I have affixed my 105 signature in presence of two witnesses.

LACEY H. EVANS.
